US0D1004223S

(12) **United States Design Patent** (10) Patent No.: **US D1,004,223 S**
(45) Date of Patent: ** Nov. 7, 2023

(54) **AIRTAG DOG COLLAR HOLDER**

(71) Applicant: **Shenzhen Guanteng Electronic Commerce Co., Ltd.**, Shenzhen (CN)

(72) Inventor: **Xiaoqing Xie**, Shenzhen (CN)

(73) Assignee: **Shenzhen Guanteng Electronic Commerce Co., Ltd.**, Shenzhen (CN)

(**) Term: **15 Years**

(21) Appl. No.: **29/897,547**

(22) Filed: **Jul. 17, 2023**

(51) LOC (14) Cl. **30-99**

(52) U.S. Cl.

USPC **D30/199**; D10/104.1

(58) **Field of Classification Search**

USPC ..... CLAIM

The ornamental design for an airtag dog collar holder, as shown and described.

DESCRIPTION

FIG. 1 is a front perspective view of an airtag dog collar holder, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the airtag dog collar holder, which form no part of the claimed design.

1 Claim, 7 Drawing Sheets
